UNITED STATES PATENT OFFICE

FRED B. LINEBERGER, OF GRAND RAPIDS, MICHIGAN, ASSIGNOR TO METAL OFFICE FURNITURE COMPANY, OF GRAND RAPIDS, MICHIGAN, A CORPORATION OF MICHIGAN

FILE-DRAWER COMPRESSOR

Application filed November 28, 1927. Serial No. 236,143.

This invention relates to a compressor or follower used in a filing drawer. Drawers in which material is filed are usually equipped with so-called follower means for the purpose of maintaining the material filed in a compact condition, thereby obviating such material buckling downward and becoming wrinkled and bent and hard of access when it is to be examined. The follower or compressor is mounted within the filing drawer for movement longitudinally back and forth therein so that it may maintain the filed material in upright compact form whether a greater or less amount of such material is received within the drawers.

It is an object and purpose of the present invention to provide a novel form of mounting for followers of the character outlined, of simple and practical structure, and equip the same with means for releasably securing the follower in any position to which it is moved lengthwise of the drawer. Various other objects and purposes, together with novel construction for attaining the same will appear fully and in detail as an understanding of the invention is had from the following description taken in connection with the accompanying drawings, in which,

Fig. 1 is a longitudinal vertical section through a filing drawer equipped with my invention.

Fig. 2 is an enlarged transverse vertical section substantially on the plane of line 2-2 of Fig. 1, looking in the direction indicated by the arrow and illustrating the follower in locked position.

Fig. 3 is a view similar to that shown in Fig. 2, but with the follower unlocked for movement lengthwise of the drawer, and

Fig. 4 is a fragmentary horizontal section and plan view, the section being taken substantially in the plane of line 4-4 of Fig. 2.

Like reference characters refer to like parts in the different figures of the drawing.

The filing drawer is of sheet metal pref-

erably, though the invention is applicable to drawers made of other material quite as well, and includes a bottom 1, vertical sides 2 turned upwardly at the edges of said bottom, a front end 3 of conventional construction 50 and a rear end 4. The sides 2 a short distance below their upper edges are formed with outwardly pressed portions 5 whereby a longitudinal groove is made at the inner side of each side of the drawer, as fully shown in 55 Figs. 2 and 3.

Within the grooves 5 a sheet-metal guide member is mounted, including a vertical leg 6 turned inwardly at its lower edge and then rebent as indicated at 7 thereby forming a 60 channel portion at the lower part of the guide. One of these guides is located in each groove at the upper portion thereof, the upper edges of the vertical legs 6 coming against the upper flanges of the groove portions 5. A 65 bar 8 is slidably mounted in each guide, its lower edge being received in the channel section thereof while its upper edge is in engagement with the under side of the upper flange of the groove 5, as shown.

The follower or compressor is made of sheet metal and comprises a plate 9 provided between its upper and lower edges with rearwardly pressed channel 10 which extends horizontally across the plate lying in substantially the same horizontal plane with the slide bars 8. Angle bars 11 are permanently secured to the front side of the channel web 10 by spot-welding or other equivalent securing means, the outer ends of 80 the angle bars being bent at right angles to extend forward and lie against the inner sides of the slides 8 to which they are permanently secured by welding or other equivalent fastening. It is evident that the follower is thus 85 slidably mounted for movement lengthwise of the filing drawer, the slides 8 normally having free sliding movement in the guides and channel sections thereof in which they are located. The upper edge of the follower 90

plate 9 is bent backwardly for a short distance and then in a downward direction, as indicated at 12, thereby eliminating a sharp narrow upper edge to the follower plate and 5 also serving another purpose which will later appear.

A vertical slot 13 is cut in the channel web 10 substantially midway between its ends through which a pin 14 passes. Two locking 10 bars 15 overlap each other at their adjacent ends through which ends the pin 14 passes. The locking bars extend outwardly and toward their outer ends each is provided with a short longitudinal slot 16 through which a headed 15 pin 17 passes, said pins being permanently secured to and extending rearwardly from the channel web 10. An operating plate 18 of flat metal overlaps the adjacent ends of the locking bars 15 with the pin 14 passing there- 20 through. The upper end of the plate 18 passes upwardly through a slot in the upper edge portion 12 of the follower plate and is then curved to the rear as indicated at 19 to provide a finger hold. On pulling upward 25 on the finger hold 19 the pin 14 traverses the slot 13 and turns the locking bars 15 about the axes of the pins 17, whereupon the outer ends of the bars 15 are moved to the position shown in Fig. 3 out of engagement with the 30 rebent lower edges 7 of the guides for the bars 8. But on pressing downward against the upper end of the plate 18 the bars are moved to the position shown in Fig. 2 and their outer ends brought against the rebent portions 35 of the guides, pressing the same outwardly and making a secure frictional engagement between said rebent portions 7 and the sliding bars 8 which hold said bars against sliding movement.

40 It is evident that the follower, when the locking bars are in the position shown in Fig. 3, may freely move with the sliding movement of the bars 8 in the guides provided therefor; and that by merely pressing downward on the 45 upper plate 18 the follower is locked in any position to which it has been adjusted. The construction is very simple, but is very practical, durable and effective for the purposes for which it is designed. Various modifications 50 in minor details of structure may be resorted to without departing from the invention defined in the claims appended hereto, and my invention is to be considered comprehensive of all forms of construction coming 55 within the scope of said claims.

I claim:

1. In combination with a drawer having a bottom and spaced apart vertical sides, horizontal guides at the inner sides of said sides 60 of the drawer, slides mounted in said guides, a follower member, connections between said follower member and slides, and manually operable means mounted on said follower member movable into and out of engagement 65 with said guides to clamp the same against

said slides and lock the follower member in any position to which adjusted or to release said follower member for movement to different positions.

2. In a construction of the class described, 70 a filing drawer having a bottom and vertical spaced apart sides, longitudinal guides attached one to the inner side of each side of the drawer, each at its lower edge portion being U-shaped in cross section, a slide bar 75 mounted in each guide, a follower member located within and transversely of said drawer, a means permanently connected to said follower member at each of its opposite vertical edge portions and to said slide bars, and manually operable means mounted on the follower member movable in one position to bear against the inner lower U-shaped portions of 80 said guides to clamp the inner legs thereof against said slide bars, said manually operable means being operable to another position out of engagement with said guides.

3. In a construction of the class described, 85 a filing drawer having a bottom and vertical sides, channel like guides attached one at the inner side of each side of the drawer, the lower flanges of said guides being rebent whereby each guide at its lower portion is U-shaped in cross section, a slide bar mounted for free 90 sliding movement in each guide, a follower member located within and transversely of the drawer, means permanently connecting said follower member to said slide bars, two diverging locking bars pivotally and slidably 95 mounted on the follower member at points between the ends thereof, the inner ends of said bars being pivotally connected together, and an operating member connected with said locking bars at their points of pivotal connection extending vertically and manually operable to turn said locking bars about their 100 points of pivotal and slidable connection to the follower member, in one position bringing the outer ends thereof against the inner legs of said U-shaped lower portions of the guides 105 to clamp the same against the slide bars, and in another position being out of engagement with said guides.

4. In combination with a drawer, a follower member, a guide on the drawer having a channel portion, a slide fixed to said follower and slidable in said channel portion of said guide, and manually operable means for pinching the channel portion of the guide against the slide to hold the slide and follower immovable.

5. In combination with a drawer, a follower member, a guide on the drawer having a channel portion, a slide fixed to said follower and slidable in said channel portion of said guide, and manually operable means mounted on the follower for pinching the channel portion of the guide against the slide to hold the slide and follower immovable.

6. In combination with a drawer having 130

vertical sides, a follower, guides fixed to the respective sides of the drawer each having a channel portion, slides fixed to said follower and slidably mounted in said channel portions thereof of said guides, and manually operable clamping members mounted on said follower and adapted to engage the channel portions of the guides and to pinch them against the slides to hold the slides and follower immovable.

10 In testimony whereof I affix my signature.
FRED B. LINEBERGER.
